H. J. KUHLMAN

OPERATING MEANS FOR PUMP JACKS

Filed Nov. 5, 1923.

Fig. 2.

Fig. 1.

H. J. Kuhlman, by
G. Kennedy,
Attorney

UNITED STATES PATENT OFFICE.

HENRY J. KUHLMAN, OF COLESBURG, IOWA.

OPERATING MEANS FOR PUMP JACKS.

Application filed November 5, 1923. Serial No. 672,881.

To all whom it may concern:

Be it known that I, HENRY J. KUHLMAN, a citizen of the United States of America, and a resident of Colesburg, Delaware County, Iowa, have invented certain new and useful Improvements in Operating Means for Pump Jacks, of which the following is a specification.

My invention relates to improvements in operating means for pump-jacks, and the object of my improvement is to supply a mechanical movement device intermediate a prime mover and a pump-jack or the like, adapted to act with more power differentially upon the pump-jack during the power impulse than during the idle return movement thereof.

Said object also comprehends an improvement upon the mechanical movement which was patented to me by the United States under Patent Number 1,412,183, April 11, 1922, by the inclusion in the mechanism of an improved form of rack-sector pitman adapted to permit assembling and housing the device in small space.

The above object I have accomplished by the means and mechanism which are hereinafter described and claimed, and which are illustrated in the accompanying drawings, it being understood that changes in the precise embodiment of invention herein disclosed can be made within the scope of what is claimed without departing from the spirit of the invention.

In said drawings, Fig. 1 is a front end elevation of this device, with the housing cover removed, and with parts sectioned or broken away or removed, and Fig. 2 is a rear end elevation of the irregularly toothed gear-wheel and its two-part driving pinion. Fig. 3 is a rear elevation of the lower member of the swinging element or rack, showing its sliding engagement with the crank-pin and the intermeshing of its rack with the teeth of the rack-sector.

The numeral 4 denotes a hollow housing open at the front, with the cover removed. The upper part of the housing has a bearing-opening to seat a short pinion-shaft 1, the latter having on its outer end a belt-wheel 2 carrying a driving-belt leading to a driving pulley not shown to be rotated positively by a suitable prime mover, such as an internal combustion engine.

Within the hollow of the housing a relatively large gear-wheel 8 is fixed on a

stub-shaft 9 rotatable in a suitable bearing not shown and has on its front face a crank-pin 15, on which is pivotally mounted a rack-sector 17 having face-teeth 18, and secured by a sleeve or collar 14 and a split-pin 16. The teeth 18 should extend about a semi-circular arc.

Opposite edge parts of the gear 8 have teeth 10 which from a medial point of each range thereof project at progressively lessening radii to each end of each range, that is, eccentric relatively to the gear 8. On the opposite or rear face of this gear arcuate marginal parts 12 project rearwardly and carry outwardly projecting teeth 13, the ranges of which are between the ends of the other ranges of teeth 10 but set off therefrom rearwardly, although the end teeth of the abutting ranges are carried across the gear edge, but in order to insure a stronger structure to the gear, its marginal edge at 11 between the ranges 10 is circumferentially smooth.

A two-part pinion composed of the two pinions 5 and 6 are rigidly connected integrally or otherwise and fixedly mounted upon the shaft 1 within the housing above the gear 8, the smaller pinion 5 being mounted eccentrically upon said shaft as is also the other pinion 6, the pinions having two teeth 7 in common which extend across both. The teeth of the pinion 5 mesh with the ranges of gear teeth 10, while the teeth of the pinion 6 mesh with the ranges of teeth 13.

A cross-shaft 19 is rotatably mounted in a bearing in the upper part of said housing to project at both ends and serves as a rock-shaft, and on both ends of this shaft an arm 24 having a terminal split 25 is fixedly clamped by means of a bolt 26. In the outer end of this arm may be supplied a number of longitudinally-aligned holes 27 for adjustably receiving a pintle-bolt 28 which pivotally connects thereto one end of a connecting-rod 29, the other end of the rod being connected by means of a pintle 30 to an element to be reciprocated, such as a pump-jack 31.

On the intermediate part of the rock-shaft 19 the upper end of another arm 20 fixed to depend within the housing hollow and carries a longitudinal rack 23 which meshes with the teeth 18 on the rack-sector 17. This arm 20 has a longitudinal slot 22 in a widened lower part 21 which is spaced in

parallel from the rack-teeth 23 and which slidingly receives the extremity of the crank-pin 15 therethrough.

It is unnecessary here to specifically describe the operation of the pump-jack by reason of the employment of the coacting two-part pinions 5—6 and the gear-wheel 8, whereby said gear is rotated at differential speeds to thus impart slower but a more powerful impulse upon the pump-jack in its working stroke, as this mechanical movement is in construction described and covered by my hereinbefore mentioned patent.

As the gear-wheel 8 rotates, its crank-pin 15 slides within the slot 22 of the swinging arm 20—21 swinging the latter to and fro, likewise rocking the shaft 19 and the arm 24, to thus reciprocate the connecting-rods 29 and the pump-rod 31.

20 The rack-sector teeth 18 in meshing with the rack-teeth 23 insure such a moving engagement therebetween as to prevent any slipping and keep the parts together to always function the same in each of the related

25 positions thereof while moving. It will be observed that this expedient of positively actuating the swinging arm 20—21 by means of the intermediate rack-sector, which might be termed a species of pitman from the 30 crank-pin 15 radially to those teeth 18 which may be in mesh with the rack teeth 23, does away with the necessity for use of a relatively long pitman connected to the gear 8, so that the mechanical movement gearing and 35 related elements may be all positioned within a relatively small housing 4 compactly, where the hollow of the housing may be filled with a liquid lubricant and need but infrequent attention, as necessary when the device 40 is actuated by means of a wind-wheel in pumping.

Having described my invention, what I claim as new, and desire to secure by Letters Patent, is:

45 1. In combination, a rotatable body having a crank-pin thereon, a medially pivoted device having on one member a longitudinal rack and a longitudinal slot opposite thereto, and a rack-sector pivotally mounted on 50 said crank-pin and meshed with said rack,

said crank-pin extending loosely into said slot.

2. In combination, a rotatable body having a crank-pin thereon, a medially pivoted device having on one member a longitudinal 55 rack and a longitudinal slot opposite thereto, a rack-sector pivotally mounted on said crank-pin and meshed with said rack, said crank-pin extending loosely into said slot, a reciprocatory body, and a connecting-rod 60 pivotally connected between and to both said reciprocatory body and the other member of said pivoted device.

3. In combination, a rotatable body having a crank-pin thereon, a medially pivoted 65 device having on one member a longitudinal rack and a longitudinal slot opposite thereto, a rack-sector pivotally mounted on said crank-pin and meshed with said rack, said crank-pin extending loosely into said slot, a 70 reciprocatory body, and a connecting-rod adjustably and pivotally connected between and to said reciprocatory body and the other member of said pivoted device.

4. In combination, a rotatable body having a crank-pin thereon, means for rotating said body at varying rates of speed during each rotation, a swinging arm having a longitudinal rack and having a longitudinal slot opposite said rack to slidingly receive 80 the crank-pin and a rack-sector pivotally mounted on said crank-pin and meshing with said rack.

5. In combination, a rotatable body having a crank-pin thereon, means for rotating 85 said body at varying rates of speed during each rotation, a medially pivoted device having on one member a longitudinal rank and having a slot parallel therewith, a rack-sector pivotally mounted on said crank-pin 90 and meshed with said rack, said crank-pin extending slidingly into said slot, a reciprocatory body, and linking-connections between another member of said pivoted device and said reciprocatory body, and adjustably pivotally connected to said member.

Signed at Waterloo, Iowa, this 1st day of November, 1923.

HENRY J. KUHLMAN.
